Primary Examiner — Mitchell I. Siegel

(57) **CLAIM**

The ornamental design for a gaga ball pit as shown and described.

DESCRIPTION

FIG. 1 is a bottom perspective view of a gaga ball pit, showing my new design;

FIG. 2 is a top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a detailed view taken from the encircled portion labeled "9" in FIG. 2; and,

FIG. 10 is a detailed view taken from the encircled portion labeled "10" in FIG. 2.

The short-dash and long-dash broken lines in FIGS. 2, 9, and 10 denote the boundaries of the detail areas and form no part of the claimed design.

1 Claim, 10 Drawing Sheets
